GIRDLE OR THE LIKE

Filed Sept. 30, 1947

UNITED STATES PATENT OFFICE

2,575,460

GIRDLE OR THE LIKE

Fred Niedermann, Rockville Centre, N. Y., assignor to Mastercraft Foundations, Inc., New York, N. Y., a corporation of New York

Application September 30, 1947, Serial No. 777,025

3 Claims. (Cl. 2—37)

1

This invention is a new and improved elastic girdle or the like, and is applicable to any garment having a girdle portion.

It is an object of the present invention to provide a girdle or the like of light weight construction capable of doing the job of a relatively heavy weight girdle.

It is a further object of the present invention to impart to the garment a controlling feature in the abdomen and buttocks by restricting the stretch in portions of the garment through inverting certain of the elastic panels thereat.

It is a still further object of the present invention to provide a girdle or like garment having restrictive sections where they are most needed for body control.

Another object of the present invention is to assemble into a garment individually stitched layers of power net material, that is, knitted or woven material wherein the stretch is restricted in or limited to one direction.

Still another object of the present invention is to provide a girdle wherein the pockets in which the stays fit are made of Lastex material so as to permit complete freedom of movements of the pockets when the garment is worn.

Other objects and advantages will be in part obvious from the annexed drawing and in part hereinafter indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the modifications in structure and relation contemplated by this invention, a drawing depicting a certain form of the invention has been annexed as a part of this disclosure, and in such drawing, like characters of reference denote corresponding parts throughout all the views, of which:

Fig. 1 is a front elevation of a garment according to the invention.

Fig. 2 is a rear view thereof;

Fig. 3 is a view of the garment turned inside out to better show the interior of the front portion thereof.

Fig. 4 is a view of the garment similar to Fig. 3, to better show the interior of the back portion thereof.

Reference now will be made more particularly to the drawing, bearing in mind that Figs. 3

and 4 show the garment in inside-out position, disclosing the interior of the garment and the disposition of the panels hereinafter described with reference thereto. The garment comprises generally of a front panel 10 connected to a rear panel 11 by the side vertical seams 12, 13 reinforced by the vertical elastic strips 14, 15, respectively, the said vertical strips being in turn stitched to the said panels by the lines of stitching 16, 17, respectively. At the upper portion of strip 14, there is provided the usual flexible bone or stay insert (not seen) located in a pocket formed by strip 14 and a strip of fabric 18. On either side of the vertical medial line of the garment and disposed over the front panel is a reinforcing panel 19 defined by the stitches 19a, 19b, by which these panels are secured to front panel 10 and the unstitched edge 19c. As clearly seen in Fig. 3, reinforcing panels 19 do not entirely cover the front panel 10, but are short of the vertical medial line and the top of the garment, leaving an area on both sides of this vertical medial line unreinforced by panels 19, and the side areas A unreinforced or of single thickness. Disposed over panels 19 are the shorter reinforcing panels 20 defined by the free edge 20b and the stitches 20a, 20c by which together with stitching 20e panels 20 are secured to the panels 19 and 10. Panels 20 are disposed to the left and right respectively of the vertical medial line of the garment, and are preferably somewhat narrower than panels 19 and are located nearer the top than the bottom of the garment. Overlying the vertical medial line of the garment (where, so far, there is only one thickness of material, namely, that of front panel 10), and overlying the seams or stitching 19b and 20b of panels 19, 20, is a centrally reinforcing panel 21 which extends the length of the front side of the garment and which is defined by the stitching 21a, 21b, 21c, and by which it is secured to the panels 20, 19 and 10. Center panel 21 preferably is provided with an intermediate portion having inwardly directed arcuate sides defined by the portions 21b¹ of stitching 21b, the upper tapering end defined by the portions 21b² of stitching 21b, and the lower tapering end defined by the portion 21b³ of stitching 21b. The upper tapering end preferably is wider than the lower tapering end of panel 21. Overlying and secured with panels 21, 20, 19 and 10, is the inner, substantially diamond-shaped reinforcing panel 22 defined by the stitching 22a, 22b, 22c, 22d. Inner panel 22 extends across substantially

the entire width of front panel 10 and is much closer to the top than the bottom of the garment.

Thus, upper-side areas A have a single thickness of material (front panel 10); upper center area B has a double thickness of material (front panel 10 and upper center panel 21) in which area B extend the parts of the edge portions 19c of panels 19; and lower area C has a double thickness of material in which area C extend the lower parts of the edge portions 19c of panels 19. The abdominal area of the garment bounded by the stitching 22a, 22b, 22c, 22d has its intermediate or central portion D comprised of three thicknesses of material (front panel 10, center panel 21 and inner panel 22), in which area D extend intermediate parts of the edge portions of panels 19 and 20; and its lateral portions E comprised of four thicknesses of material, namely, front panel 10, inner panel 22, and intermediate panels 19 and 20. Running down vertically from the center of the abdominal area of the garment is a pocket formed between the elastic strip 30 and portions of the panels adjacent thereto by stitching 30a, in which pocket there is disposed the usual flexible bone or stay insert (not seen). On either side of the pocket formed by the elastic strip 30 and extending downwardly a relatively short distance from the top of the garment, are vertical pockets formed between the strips 31 and the panels adjacent thereto, in which are disposed the usual stay or bone inserts.

Overlying back panel 11 is a reinforcing inner panel 32 extending the length of panel 11, but shorter in width thereof. Panel 32 preferably has arcuate lateral edges secured to panel 11 and the arcuate lateral edges of inner side panels 33 by the lines of stitching 32a. Panel 32 preferably has a V-shaped cut-out at its top center at which panel 32 is further secured to panel 11 by the lines of stitching 32b stitched to back panel 11. Panels 33 have slanting top edges secured to back panel 11 by the lines of stitching 33a.

The upper portion of a side of the garment is slitted as indicated at 34 and is provided therewith the usual complementary fastening means or zipper 35. Adjacent slit 34, the garment is provided with the usual fabric flap 36 adapted to cover the said fastening means. The bottom of the garment is reinforced by an elastic tape or band 40 extending completely around the bottom of the garment and secured to the panels adjacent thereto by the lines of stitching 41. Secured at band 40 at convenient places and between said band 40 and fabric strips 42 are the usual hose supporters 43. The top of the garment is reinforced by an elastic strip or tape 44 which extends around the top of the garment, but is separated at the slit 34 of the garment to facilitate placement of the garment upon the body of the wearer. It is understood that the stitchings for the panels and reinforcing tapes comprise zigzag stitches in order to allow the garment to remain elastic at the panel seams and tapes.

It is not intended to limit the invention to any particular type of one-way or two-way stretch material, woven or knitted or netted. The fabric preferably selected for the panels 10, 11, 19, 20, 22, 33 is designated in the trade as "power net," which is a netted fabric in which the main parallel elastic threads are connected by much shorter lateral elastic or non-elastic threads. The fabric preferably selected for the panels 21 and 32 is known in the trade as "leno" or one-way stretch elastic material. However, it is not intended that the material of which the panels

may be made be so limited. The "power stretch" and power stretch direction as used in the description and claims of the specification may be defined respectively as the desired effective stretch and as the direction in which the desired effective stretch takes place. In the preferred embodiment shown and described herein, the "power stretch" in panels 10, 19, 20 and 22 at the front of the garment and in panels 11 and 33 at the rear of the garment, preferably takes place in horizontal direction; and the "power stretch" in panel 21 at the front of the garment and in panel 32 at the rear of the garment, preferably takes place in vertical direction; that is, panels 10, 11, 19, 20, 22 and 33 each embody a power stretch in horizontal direction and panels 21 and 32 each embody power stretch in vertical direction. However, panel 22 or any of the panels having a power stretch in horizontal direction may be arranged to have its power stretch in vertical direction, a purpose of the invention being, to so dispose the panels that the direction of power stretch in one or more of the panels may be arranged at substantially right angles to the direction of power stretch in the remaining panels.

Thus there has been provided a garment which is lightweight and flat in construction, capable of performance of a heavy weight girdle or the like, and which has restrictive sections where they are most needed. By arranging the panels relative to their power stretch effectiveness, the garment is productive in controlling the abdomen and buttocks of the wearer.

What is described as new and described to be secured by Letters Patent is:

1. A girdle comprising an elastic front main panel and an elastic rear main panel joined together at their side edges to provide a tubular garment, a reinforcing elastic panel on either side of the vertical medial line of said front panel extending from said side edges and terminating short of said medial line, said reinforcing panels extending substantially the length of said front panel, a reinforcing elastic panel overlying a portion of each of the first mentioned reinforcing panels and terminating short of the front edge of the latter, a reinforcing elastic center panel overlying the center of said front panel and overlying the front edges of the first mentioned reinforcing panels, a diamond shaped reinforcing elastic panel extending across the front panel and overlying said center panel and the first and second mentioned reinforcing panels, a reinforcing elastic rear panel disposed on either side of the vertical line of and upon said rear main panel, and a reinforcing rear center panel disposed between the confronting edges of the first mentioned reinforcing rear panels.

2. A girdle comprising an elastic front main panel and an elastic rear main panel joined together at their side edges to provide a tubular garment, a horizontally stretchable reinforcing elastic panel disposed on either side of the vertical medial line of said front main panel extending from the side edges thereof and terminating short of said medial line, each of said reinforcing elastic panels extending from the bottom of said front main panel and having its top edge disposed below the top edge of the latter, a horizontally stretchable elastic panel overlying the upper portion of each of the first mentioned reinforcing panels and extending from the side edge of said front main panel and terminating short of the front edge of said first mentioned reinforcing panel, a vertically stretchable elongated reinforcing

ing center panel overlying the center of said front main panel and extending from the top to the bottom of the latter, the side edges of said center panel overlying the front edges of said first mentioned reinforcing panels and extending to the front edges of the second mentioned reinforcing panels above and below the latter, a substantially diamond shaped horizontally stretchable reinforcing panel extending between the side edges of said front main panel and overlying portions of said first and second mentioned reinforcing panels and of said reinforcing center panel, a horizontally stretchable reinforcing panel extending from each of the side edges of said rear main panel and terminating short of the vertical medial line of the latter, and a vertically stretchable reinforcing center panel overlying the central portion of said main rear panel and terminating at its side edges in line with the rear edges of the last mentioned horizontally stretchable reinforcing panels.

3. A girdle as set forth in claim 1, wherein said side edges of said reinforcing center panel on the front main panel are concaved in the area thereof confronting the front edges of said second mentioned reinforcing panels to thereby provide a space therebetween.
